(57) **CLAIM**

The ornamental design for a stand alone billiard bridge device, as shown and described.

DESCRIPTION

FIG. 1 is an isometric view of a stand alone billiard bridge device showing my new design;

FIG. 2 is a front elevational view thereof, the front elevational view is a mirror of a rear elevational view;

FIG. 3 is a side elevational view thereof, a left side elevational view is a mirror of a right side elevational view;

FIG. 4 is a top plan view thereof; and,

FIG. 5 is a bottom plan view thereof showing my design. The crisscross texture shown inside the billiard cue holder and the bottom of the stand alone billiard bridge device forms part of the claimed design.
